UNITED STATES PATENT OFFICE.

DARYL C. HARE, OF WILKINSBURG, PENNSYLVANIA.

SWITCH.

1,175,630.

Specification of Letters Patent. Patented Mar. 14, 1916.

Application filed March 13, 1915. Serial No. 14,090.

To all whom it may concern:

Be it known that I, DARYL C. HARE, a citizen of the United States, residing at Wilkinsburg, in the county of Allegheny and 5 State of Pennsylvania, have invented certain new and useful Improvements in Switches, of which the following is a specification.

My invention relates to an improved 10 lighting system for automobiles or similar purposes, and an improvement in controlling switch mechanism therefor.

The object of the invention is to provide 15 a system of electric lamps and wiring therefor, with a controlling switch adapted to provide for various combinations of the several lamps by setting the adjustable switch element, to establish any desired series of branch circuits according to a pre- 20 determined plan, as shall be more fully hereinafter described.

Referring to the drawings.—Figure 1 represents a diagrammatic illustration of a 25 lighting system and the distributing conducting connections, switch and the controlling indicating key. Fig. 2 is a face view of the controlling switch. Fig. 3 is a vertical sectional view through the switch, indicated by the line III—III of Fig. 2. 30 Fig. 4 is a cross sectional view, indicated by the broken line IV—IV of Fig. 2. Fig. 5 is a view of the switch in edge elevation, partly broken away. Fig. 6 is a detail view 35 partly broken away, showing the operation of the adjustable conductor blade. Fig. 7 is a sectional detail view, further illustrating the operation, and showing the terminals of the conductor wires provided with enlarged bearing heads:

40 In adapting the invention to the manipulation and control of the several lamps usually incorporated with an automobile, there are present the head lamps 3', 3', the side lamps 4', 4', a dash lamp 5', a tail 45 lamp 6', and dimmers 2', 2'. The latter may be conveniently incorporated within the casing of the head lamps, and are adapted to be used when the head lights are out, the dimmer lamps being out when the head 50 lights are on. A battery 7 or other suitable source of current is wired by a conductor 8 in circuit with a conducting terminal 9 and a suitable binding post 10 arranged centrally of the controlling switch S, and 55 which may be suitably used as the central bearing for the centrally arranged rotatable

stem 11. Said stem 11 is mounted within the central portion of the insulating base of the switch S, and extends outwardly therebeyond, and beyond a suitable retaining plate 12, and is provided with a turning button terminal 13, preferably of insulating material. Between the button and the outer portion of stem 11, as by a squared shoulder, is clamped the switch blade 14, of copper 60 or other suitable conducting material. Said switch blade is preferably somewhat resilient, being arched downwardly and provided with a contacting spring terminal, and is adapted to be swung around by the 65 terminal button to any of the several various positions for engagement with each of a plurality of depressible contact buttons a, b, c, d, e, f, g, h, i, j, respectively. These buttons are depressibly inserted in 70 suitable holding openings arranged transversely through the base of the switch S by means of extended stems 15 provided at their inner ends with limiting cross pins 75 16 or other suitable abutments, so as to limit 80 their outward movement under action of cushioning springs 17. Said springs, as shown, are seated in suitable receiving recesses in the switch base and bear upwardly 85 underneath the button head of such depressible elements, so as to throw them outwardly in disengagement from the contacting terminals of the conducting wires.

The conducting wires, hereinafter referred to in detail, extend inwardly through 90 the base of the switch S and terminate by their ends 18 within range of the under face of the button (a to j), the number of the wires and their corresponding contacting terminals depending on the number of individual circuits desired to be established by 95 the depressing action of each particular button.

Between the several operating buttons, I 100 insert an inclosed bearing 19 which may conveniently be held in the base between the buttons by a screw extension 20, the object of such bearing being to provide an inclined plane, upwardly from which the spring terminal of blade 14 will ride from one depressed button over to the next button, normally in elevated position. The operation 105 of the spring depressed blade 14 in such action will be readily understood without further description, it being shifted from one button to another and retained in the particular position at which the desired 110

combination of circuits is established. In its normal inoperative position, the blade 14, as shown in Fig. 2, rests upon a neutral button 21, the remainder of its circumferential path being over a continuous annular series of inclined bearings and depressible buttons throughout.

Referring to Fig. 7, I show the inner contacting terminals of the wires as provided with an enlarged head or bearing 16' adapted to insure good contact engagement against the under-face of the button, and also show the operation of the terminal of blade 14 in passing over from the incline 19 to the top of the next adjacent button, as, for instance, *a*.

The buttons are preferably provided with an annular sloping edge *a'* and the advancing edge of the blade 14 is beveled or chamfered, as indicated at 22, to facilitate the operation.

Spring pressure of the blade 14, it will be understood, is sufficient to depress the button into engagement with the wire terminals to establish the circuit.

The several circuits are established as follows: The blade is set rotatably by its button 13, to the particular position, or over the particular button *a* to *j* respectively, according to the particular combination of lamps to be lighted, as indicated by the guide or key diagram at the top of Fig. 1. Thus, in the first position, engaging button *a*, for lighting the head and tail lamps, the circuit will pass through conductors *a*³, *a*⁶ to a common connecting conductor 3 and a similar conductor 6. Conductor 3 is connected with the head lamps by conductor 3'', in series with each of the head lamps 3'.

40 The several circuits are capable of being successively established in the same manner by manipulation of the contact blade 14. Thus, upon shifting it to button *b* for illuminating the side and tail lamps, circuit is established through conductors *b*⁴ and *b*⁶, to common conductors 4 and 6, from which conductors 4'' and 6'' lead to side lamps 4' and tail lamp 6' respectively. Circuit is established through button *c* and conductors *c*³, *c*⁴, *c*⁶ to head conductor 3, side conductor 4 and tail conductor 6, and by their separate wires to each of the particular lamps 3', 4' and 6'. The same combination of circuits is established through the several buttons *d*, *e*, *f*, and *g*, and their several individual conductors in the same manner. Thus, the conductors *d*³, *d*⁴ and *d*⁶ carry the current to head lamp 3', dash lamp 5' and tail lamp 6'.

The conductors *e*⁴, *e*⁵ and *e*⁶ carry the current to side lamp 4', dash lamp 5' and tail lamp 6'. The conductors *f*², *f*⁵ and *f*⁶ carry the current to dimmer lamp 2', dash lamp 5' and tail lamp 6'. The conductors *g*², *g*⁴ and *g*⁶ carry the current to dimmer lamp 2', side lamp 4' and tail lamp 6'. The con-

ductors from button *h* carry the current through circuit wires *h*², *h*⁴, *h*⁵ and *h*⁶ to the dimmer lamps 2', side lamps 4', dash lamp 5', and tail lamp 6'. The conductors *i*², *i*⁴, *i*⁵ and *i*⁶ from button *i* carry the current to the head lamp 3', dash lamp 5', side lamps 4' and tail lamp 6'. The final button *j* is adapted to establish circuit to each of the five lamps, or pairs of lamps, as by conductors *j*², *j*³, *j*⁴, *j*⁵ and *j*⁶ to the dimmer lamps 2', head lamps 3', dash lamp 5', side lamps 4' and tail lamp 6'.

What I claim is:

1. A switch for the purpose described having a centrally arranged pivoted resilient conducting arm adapted to be connected with a source of current, a plurality of groups of current terminals annularly arranged around the pivotal center of said arm adapted to be placed in circuit with said source of current, and a movable contact device for each of said groups adapted to be engaged by said arm and to simultaneously engage each member of a selected group.

2. A switch for the purpose described having a centrally arranged pivoted resilient conducting arm adapted to be connected with a source of current, a plurality of groups of current terminals annularly arranged around the pivotal center of said arm adapted to be placed in circuit with said source of current, and a movable spring retracted contact device for each of said groups adapted to be engaged by said arm and to simultaneously engage each member of a selected group.

3. A switch for the purpose described having a centrally arranged pivoted resilient conducting arm adapted to be connected with a source of current, a plurality of groups of current terminals annularly arranged around the pivotal center of said arm adapted to be placed in circuit with said source of current, a movable contact device for each of said groups adapted to be engaged by said arm and to simultaneously engage each member of a selected group, and bearings for said arm intervening between said contact devices.

4. In combination, an insulating base, a centrally arranged conductor having a movable contact arm, and a plurality of groups of current terminals, and a depressible contact device for each group arranged in the path of said arm adapted to simultaneously engage each member of a group.

5. In combination, an insulating base, a centrally arranged conductor having a movable contact arm, and a plurality of groups of current terminals, and a depressible spring retracted contact device for each group arranged in the path of said arm adapted to simultaneously engage each member of a group.

6. In combination, an insulating base, a centrally arranged conductor having a movable contact arm, a plurality of groups of current terminals, a corresponding plurality of depressible spring-retracted studs adapted to make contact with said current terminals successively arranged in the path of said arm, and inclined bearings for the

arm intervening between said contact devices.

In testimony whereof I hereunto affix my signature in the presence of two witnesses.

DARYL C. HARE.
